UNITED STATES PATENT OFFICE.

CHARLES A. SUTHERLAND, OF ALAMEDA, CALIFORNIA.

DESIGN FOR A BOTTLE.

41,855.

Specification for Design. Patented Oct. 24, 1911.

Application filed May 23, 1911. Serial No. 629,080. Term of patent 7 years.

To all whom it may concern:

Be it known that I, CHARLES A. SUTHERLAND, a citizen of the United States, residing at Alameda, in the county of Alameda and State of California, have invented a new, original, and ornamental Design for Bottles, of which the following is a specification, reference being had to the accompanying drawing, forming part thereof.

The figure is a front view of a bottle showing my new design.

I claim:

The ornamental design for a bottle, as shown.

CHARLES A. SUTHERLAND.

Witnesses:

FRANCIS M. WRIGHT,
N. B. KEATING.
